US0D1096311S

(12) **United States Design Patent** (10) **Patent No.:** **US D1,096,311 S**
(45) **Date of Patent:** **** Oct. 7, 2025**

(54) **CONTAINER**

(71) Applicant: **ZHEJIANG HAODA SCIENCE & TECHNOLOGY CO., LTD**, Jinhua (CN)

(72) Inventor: **Haojun Cheng**, Jinhua (CN)

(73) Assignee: **ZHEJIANG HAODA SCIENCE & TECHNOLOGY CO., LTD**, Jinhua (CN)

(**) Term: **15 Years**

(21) Appl. No.: **29/888,887**

(22) Filed: **Apr. 6, 2023**

(30) **Foreign Application Priority Data**

Mar. 8, 2023 (CN) 202330100266.3

(51) **LOC (15) Cl.** **07-01**

(52) **U.S. Cl.**

USPC **D7/510**; D7/533

(58) **Field of Classification Search**

USPC D7/509-511, 318, 531-533, 602, 396.2, D7/392.1, 396.1, 622, 623, 624.2, 300.2,

D7/709; D9/719, 741, 532; D3/202

CPC A47G 19/2205; A47J 41/00; B65D 21/02;

F17C 2270/0727

(57) **CLAIM**

The ornamental design for a container as shown and described.

DESCRIPTION

FIG. 1 is a right, front, top perspective view of a container showing my new design;

FIG. 2 is a left, rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

In the drawings, the broken lines illustrate portions of the container that form no part of the claimed design.

1 Claim, 8 Drawing Sheets
